UNITED STATES PATENT OFFICE.

DWIGHT D. McBRIDE, OF GOLDEN CITY, MISSOURI.

DOG CRATE.

Application filed August 20, 1924. Serial No. 733,210.

To all whom it may concern:

Be it known that I, DWIGHT D. McBRIDE, a citizen of the United States, residing at Golden City, in the county of Barton and 5 State of Missouri, have invented certain new and useful Improvements in Dog Crates, of which the following is a specification.

This invention relates to dog crates and the object of my invention is to provide a 10 dog crate mounted on the running board of an automobile so that a sportsman may transport his hunting dog to any desired place without the inconvenience of shipping.

Another object of my invention is the provision of a dog crate which is slightly in 15 appearance and which may be readily mounted upon and detached from the running board of an automobile without disfigurement of either the crate or the automobile.

Another object of my invention is the provision of a dog crate which is well ventilated and in which a dog may be comfortably housed during the trip to and from a hunting 25 place.

Still another object of my invention is the provision of a dog crate having an open side which may be quickly and expeditiously covered during inclement weather.

30 I accomplish the above and other objects of the invention, which will be apparent as the description proceeds, by means of the device shown in the accompanying drawings, in which

35 Fig. 1 is a perspective view of my improved dog crate;

Fig. 2 is a vertical section of the crate, the running board and adjacent side of the automobile on which it is mounted being 40 shown in dotted lines; and

Fig. 3 is a front view of the crate with the parts broken away, the sliding door section being shown in raised position.

45 In the drawings, in which like parts are indicated by like reference characters on all the figures thereof, 1 indicates the bottom of my improved crate and 2 the top thereof. The sides 3, as well as the top and bottom of the crate, are formed from wood of suitable

50 thickness, the top and bottom being of heavier stock than the sides. The rear edges of the sides slope outward from the top to the bottom of the crate, while the bottom member is made deeper than the top member. This construction provides a crate

of maximum capacity and suitable conformation for mounting on the running board of an automobile which will not bear against and thus mar the sides of the automobile.

In the four corners of the crate are 60 wooden braces 4 which provide the necessary rigidity to the crate. The back of the crate is formed from heavy rubberized material 5 which is fastened to the rear edges of the top, bottom and sides of the structure. 65

The open front 6 of the crate is constituted by a plurality of wooden bars formed from dowel stock, preferably eleven in number. The outer bars 7 are fixed at their extremities in the top and bottom members of 70 the crate, the remaining bars 8 having their extremities fixed in wooden cross pieces 9. The bars 8 and the cross pieces 9 thus provide a sliding door for the front of the crate.

75 Fastened on the outside of the top 2 is the upper edge of a curtain 10 of rubberized material which may temporarily cover the front of the crate. In order to hold the curtain in position over the front of the crate, the sides and bottom thereof and the sides and bottom of the crate are provided with cooperating members of suitable two part fastening elements 11. The top member 2 is provided with straps 12 adapted to hold the curtain in its rolled position at the top of the crate. Cooperating fastening elements are also provided on the straps and the top member as shown.

80 The crate is detachably mounted on the 90 running board of an automobile by means of iron clamps 13 which pass under the running board and are clamped thereto by means of thumb screws 14.

85 It will thus be seen that I have provided a dog crate of such construction that sportsmen may carry their dogs with them when making a hunting trip, thereby avoiding the necessity for shipping and the consequent inconveniences thereof. The crate constitutes 100 a comfortable housing for the dog in which it may be protected during all kinds of weather.

105 While I have illustrated and described the preferred form of my invention, it is to be understood that I do not wish to be limited except within the scope of the claims hereunto appended.

110 What I claim as new and desire to secure by Letters Patent is:

1. A crate adapted to be detachably fastened to and supported by the running board of an automobile, said crate comprising a top, a bottom and sides formed from rigid material, said bottom being substantially the width of the running board, the back of the crate being formed of flexible water-proof material and sloping from the top to the bottom of the crate in order to conform to the side of the automobile, the front of the crate being open, and an openwork door for said front.
- 5 2. A crate adapted to be detachably mounted on the running board of an automobile, said crate comprising rigid top, bottom and side walls, the rear wall sloping from the top to the bottom of the crate and formed of flexible, waterproof material, the front of the crate comprising a sliding door of substantially the entire extent of said front, said crate when in position on the automobile being entirely within the outlines of the running board and fenders, and a waterproof curtain for temporarily covering said front. 20 25

In testimony whereof I affix my signature.

DWIGHT D. McBRIDE.
